[57] CLAIM

The ornamental design for a connector, as shown and described.

DESCRIPTION

FIG. 1 is a perspective view of the connector;
FIG. 2 is a reduced side elevational view thereof, all sides being identical;
FIG. 3 is a reduced top plan view thereof;
FIG. 4 is a reduced bottom plan view thereof; and,
FIG. 5 is a further reduced perspective view thereof, the broken lines being shown for illustrative purposes only and forming no part of the claimed design.
